YARN PACKAGE

Alvin Lodge, Detroit, Mich., assignor to American Viscose Corporation, Wilmington, Del., a corporation of Delaware

Original application October 14, 1943, Serial No. 506,245. Divided and this application January 30, 1945, Serial No. 575,281

3 Claims. (Cl. 242—159)

This invention relates to the winding of yarn on tubes, cones or other yarn carriers and more particularly it relates to an automatically operated means for winding a reserve length of yarn on the end of the carrier before winding the yarn package. This application is a division of my prior application Serial No. 506,245, filed October 14, 1943.

It has been found advantageous to have a reserve length of yarn wound on the carriers of yarn packages to serve as a transfer tail where the yarn is used on warping or knitting machines, but where the last operation of preparing the yarn package comprises a twisting operation, there is usually at the beginning of the winding a short length of the yarn which is not uniformly twisted. It is, therefore, an object of this invention to provide automatic means for winding on the end of the yarn carrier a waste tail of sufficient length to include all the nonuniformly twisted yarn at the start of the winding prior to winding the usual transfer tail of reserve yarn, the two groups of turns of the yarn being spaced from each other and from the yarn package on the carrier.

In the drawings, which illustrate a preferred embodiment of this invention,

Figure 1 is a partial plan view of a winding machine having means for winding a waste tail and a transfer tail in accordance with this invention, the parts being positioned as at the start of winding the waste turns;

Figure 2 is a view similar to Figure 1 and showing the parts as positioned during the winding of the yarn package.

Figures 3 and 4 are partial views in elevation showing the relative positions of the yarn guides during the winding of the waste and transfer tails and during the winding of the yarn package, respectively;

Figure 5 is a view in elevation of the ratchet wheel, cam and cam follower shown in Figures 1 and 2; and

Figure 6 is a fragmentary sectional view taken as on line 6—6 of Figure 3;

Figure 7 is a face view of a wound package made in accordance with the present invention.

In the drawings, the invention is shown applied to a winding machine of known construction, only such parts of the winding machine being shown as are necessary to illustrate the application of the invention thereto. Of the winding machine there is shown the driving rollers 1 mounted at opposite sides of the machine on shafts 2 supported in suitable bearings (not

shown) carried by the machine frame which comprises a bed plate 4. The yarn carriers, shown as tubes, 6 on which the yarn is to be wound, are mounted upon shafts 8 supported so that the carriers and the yarn wound thereon rest upon the driving rollers 1 and are driven thereby. The yarn passes between each tube 6 and its roll 1 and during the winding of the body of the package, the yarn is guided by a yarn guide 10 mounted upon the traverse bar 12 which is reciprocated throughout the winding operation so as to distribute the yarn on the tube.

To receive the waste and transfer turns of the yarn, each tube 6 is formed with spaced grooves 6a and 6b at one end of the tube and the yarn is guided to the grooves of each tube by means of a yarn guide 14 mounted on a bar 16 which is supported by spaced links 18 pivotally connected to the bar 16 and a bar 20 carried by the machine frame. A spring 22 connected to an end of the bar 16 and to the machine frame biases the bar 16 to a position as shown in Figure 4, while a pin 24 mounted in an end of a lever arm 26 and engaging between pins 25 and 27 fixed in the bar 16 controls the movement of the bar 16.

The lever arm 26 is one arm of a substantially T-shaped lever pivotally mounted as at 28, on the bed plate 4 and having an arm 26' extending to the opposite side of the machine and provided with a pin 24' engaging between pins 25' and 27' fixed in a bar 16' to control the operation of the same simultaneously with the operation of the bar 16, the bar 16' being mounted similarly to the bar 16 and having yarn guides 14 mounted thereon. The T-shaped lever is also provided with a curved arm 30 having spaced pins 31 and 33 projecting upwardly therefrom at its outer end and an upwardly projecting cam follower 32 positioned inwardly from the pins 31 and 33.

The cam follower 32 is positioned to engage a cam 34 mounted for rotation about a bolt 36 fixed in the bed plate 4. A spring 21 coiled about a hub attached to the cam and having one end engaged with the base plate 4 and its other end engaged with the cam 34, opposes the rotation of the cam in a clockwise direction. The cam 34 is a flat circular disk having an irregular sector-like portion cut away and providing a circular cam face 341 extending approximately 270° and a short cam face 342 of less radius than the larger cam face 341. Bolts 33 and springs 35 surrounding the bolts yieldingly secure a stop member 23 to the cam 34 where the portion has been cut away, the member 23 projecting radially of the cam 34 to engage with the cam follower 32.

Secured to the upper surface of the cam disk 34 is a ratchet wheel 40 arranged to be engaged for operation in a clockwise direction by a pawl 42 pivotally mounted at an end of a lever 44 which is pivotally mounted on the bolt 36 supporting the cam 34. A spring 46 engaging the pawl 42 and its pivotal support biases the pawl to engage the ratchet wheel 40.

The opposite end of the lever 44 is engaged by a lever arm 48 fixed on a shaft 50 suitably journaled in the machine frame. Also fixed on the shaft 50 is a lever arm 52 positioned to engage a cam 54 fixed on the roller shaft 2. A spring 56 secured to the upper end of the lever 48 and the adjacent end of the lever 44 holds these levers in engagement while a spring 58 secured to the lever 52 and to the machine frame tends to hold the lever 52 in engagement with the cam 54. A locking dog 60 pivotally mounted on the bed plate 4 is biased by a spring 62 to engage with the ratchet wheel 40 and prevent rotation of the ratchet wheel and cam 34 in a counter-clockwise direction by the spring 21. Mounted on the dog 60 is an adjustable abutment 64 positioned in the plane of the lever arm 30.

When the mechanism is operating to wind the waste tail on the tube and the parts are positioned as shown in Figure 1, the follower 32 on lever 30 bears against the cam face 341 at or adjacent the stop member 23, pawl 42 is positioned to engage ratchet wheel 40, lever 52 bears against cam 54 and pin 24 on lever 26 bears against pin 25 and holds bar 16 pressed to the right, as seen in Figures 1 and 3, so that the yarn guides 14 are aligned with the outer grooves 6a on the tubes 6 and the bar 16 is raised by the links 18 against the action of spring 22. With the shaft 2 operated to rotate rolls 1 and tubes 6 to wind the yarn in the outer groove 6a of each tube 6, rotation of cam 54 operates lever 52, once for each revolution of shaft 2 and, through shaft 50, lever 48 and lever 44 operates the pawl 42 to rotate the ratchet wheel 40 step by step in a clockwise direction and shift the cam 34 against the action of spring 21. The winding of the yarn in the outer groove 6a continues as the cam 34 is moved around step by step until the follower 32 passes from the cam face 341. As the follower 32 passes from the cam face 341, spring 22 shifts the bar 16 to move the yarn guide 14 to the left until it is aligned with the inner groove 6b and at the same time, through the engagement of pin 25 with pin 24, shifts the levers 26, 30 so as to bring the follower 32 into contact with the cam face 342. Cam face 342 limits the movement of the levers 26, 30 and bar 16 and holds the yarn guide 14 aligned with the inner groove 6b.

Continued operation of the shaft 2 causes the yarn to be wound in the groove 6b and continues the stepping around of the cam 34 until the cam face 342 passes from beneath the follower 32 permitting the spring 22 to shift the bar 16 further to the left and to cause the follower 32 to move into the cutaway portion of the cam 34. This movement of lever 30 brings pin 23 against lever 44, causing lever 44 to rotate on the bolt 36 and, through spring 56, to rotate lever 48, shaft 50 and lever 52, lifting lever 52 from the cam 54 against the action of spring 58 and preventing further operation of the lever 52 by the cam 54. Locking dog 60 remains in engagement with the ratchet wheel 40, as shown in Figure 2, and prevents spring 21 from shifting the cam 34 or ratchet 40 from the position to which it was moved by the pawl 42.

Throughout the operation of the machine, the traverse bar 12 has been reciprocated, carrying with it the yarn guide 10. The second movement to the left of the bar 16 by the spring 22 shifts the yarn guide 14 from the groove 6b and, at the same time, lowers the bar 16 and yarn guide 14 as the supporting links 18 pivot about their connection to the fixed bar 20. This movement of the yarn guide 14 positions the yarn to be engaged by the yarn guide 10, the yarn passing up the inclined side of yarn guide 10 and being retained in the slot thereof. Continued movement of the yarn guide 10 thereupon distributes the yarn upon the tube 6 during the winding of the package in the usual manner.

Upon replacement of filled tubes with empty tubes, the levers 26, 30 are operated by means of handle 66, rotating the lever 30 about the pivot 28 and shifting bar 16 to the right to raise the bar 16 and align the yarn guide 14 with the groove 6a. Rotation of the lever 30 removes pin 23 from the lever 44 and engages pin 21 with the pawl 42 to disengage the pawl from the ratchet wheel 40 permitting spring 58 to return lever 52 to engagement with cam 54 and shifting levers 48 and 44 with lever 52. Continued movement of the lever 30 engages the lever with the abutment 64 on the locking dog 60 and disengages the dog 60 from the ratchet wheel 40. Disengagement of the dog 60 from the ratchet wheel permits the spring 21 to rotate the cam 34 and ratchet wheel 40 counter-clockwise until the stop member 23 on the cam 34 engages the cam follower 32; thus causing the cam 34 to be returned to its starting position. The springs 59 on bolt 36 cushion the blow of the stop member 23 and prevent damage to the various parts. The parts are now in starting position and upon placing the yarn in the yarn guide 14 and securing the end of the yarn so it will wind upon the tube 6, the cycle of operations is repeated.

The return of the cam 34 to its initial position for the start of each winding operation insures uniform lengths of the waste and transfer tails being wound at each operation. When the yarn package is used, severing the yarn between the waste and transfer tails insures transfer tails of uniform length and uniform twist throughout.

The completed package of the present invention is shown in Figure 7 and comprises the waste tail A in groove 6a, the transfer tail B in groove 6b and the main winding C on the body of the tube 6. The waste tail has varying twist, whereas the transfer tail B has the full twist throughout its length.

What is claimed is:

1. The combination of a yarn carrier, a yarn package and transfer and waste tails on the carrier, said transfer and waste tails being spaced from the yarn package and from each other.

2. The combination of a yarn carrier, a yarn package and transfer and waste tails on the carrier, said transfer and waste tails being spaced from the yarn package and from each other, all of the yarn in the transfer tail having substantially the same twist as that in the package.

3. The combination of a yarn carrier, a yarn package and transfer and waste tails on the carrier, said transfer and waste tails being spaced from the yarn package and from each other, all of the yarn in the transfer tail having substantially the same twist as that in the package, and a portion of the yarn in the waste tail having less twist than that of the transfer tail.

ALVIN LODGE.
